UNITED STATES PATENT OFFICE

2,657,928

TOY MERRY-GO-ROUND

Lloyd L. McDonald, Shamrock, Tex.

Application May 28, 1951, Serial No. 228,608

3 Claims. (Cl. 272—31)

1

The present invention relates to toys and more particularly to a toy merry-go-round providing an amusement device for children.

An object of the present invention is to provide a toy merry-go-round which simulates a full scale merry-go-round, embodying means for effecting vertical reciprocation of the simulated animals or "flying horses" in the same manner as in conventional "flying horses."

Another object of the present invention resides in the provision of means for effecting rotation of the platform supporting the simulated animals and to which the top is secured, that means providing a common means for actuating a music making means.

A still further object of the present invention is to provide an amusement toy which will be pleasing in appearance, easily manufactured and readily assembled or disassembled.

Various other objects and advantages will become apparent from the detailed description to follow. The best form in which I have contemplated applying my invention is clearly illustrated in the accompanying drawings, wherein:

Figure 1 is a side elevational view of the toy merry-go-round of the present invention;

Figure 2 is a horizontal transverse sectional view taken substantially along the plane of line 2—2 of Figure 1;

Figure 3 is a vertical transverse sectional view taken substantially along the plane of line 3—3 of Figure 2; and,

Figure 4 is a diagrammatic view of the electrical system employed in the toy merry-go-round of the present invention.

Referring more particularly to the drawings, wherein like numerals designate like parts throughout, the numeral 10 designates generally the toy merry-go-round of the present invention which is seen best in its entirety in Figure 1. The toy merry-go-round 10 is comprised of a supporting base 12, a drive means 14, music making means 16 and the numeral 18 designates generally the rotatable support for the simulated "flying horses."

Looking now at Figures 2 and 3, the supporting base 12 will be seen to comprise a substantially cylindrical element 20 having a flat circular plate 22 secured to its upper edge. The plate 22 is formed with a centrally disposed recess 24 in which a cup-shaped bearing element 26 is fixedly disposed.

An upper bearing means is supported on the plate 22 and includes the upper bearing plate 28 having a central opening 30 formed therein.

A plurality of inclined support rods 32 interconnects the plate 28 with the plate 22 and maintains the same in spaced parallel relation with the opening 30 coaxial with the recess 24. The outer periphery of the plate 28 is formed with beveled gearing 34, while the upper surface of the plate 28 is formed with a pair of concentric electrically conductive annular rings 36 and 38.

The cylindrical member 20 has a switch box 40 carried thereby, the switch being operated by the manually operable switch element 42 disposed exteriorly of the cylindrical member 20. Electrical conductors 44 and 46 encased in the insulating covering 48 connect the switch box 40 with their respective annular rings 36 and 38.

The rotatable means 18 upon which the simulated "flying horses" are supported includes the upper circular plate 50 having the bars 52 formed integrally therewith at the center with the bore 54 formed therethrough. A lower annular disk 56 is connected to the upper disk 50 by a plurality of spacer rods 58 which maintain the upper and lower disks in spaced parallel relation.

The means for supporting the upper and lower disks for rotation on the base 12 includes the standard 60 which has its lower end received within the cup-shaped bearing element 26 for engagement on the ball bearing 62. An upper intermediate portion of the standard 60 has the upper disk 50 secured thereto by the pin 64 extending through the bar 52.

Secured to a lower portion of the standard 60 is a sleeve 66, a pin 68 extending therethrough, and gear 70 formed integrally with the sleeve 66. An electric motor M is supported on the plate 22 within the annular disk 56 and has a pinion 72 carried by its drive shaft 74. The pinion 72 is engaged with the gear 70 for effecting rotation of the standard 60.

Also fixedly secured to the standard 60 is a pulley sheave 76. A conventional music box 78 is disposed on the base plate 22 and has a pulley sheave 80 carried by its drive shaft 82. The pulley 80 is operatively connected to the pulley 76 by means of the belt 84, whereby rotation of the standard 60 effects music making.

Secured to the periphery of the upper disk 50 is a cylindrical member 86 having a plurality of mirrors 88 secured thereto to give a pleasing appearance and simulating the appearance of a conventional merry-go-round. A substantially conical top 90 is formed with an opening 92 at its upper end. The upper and lower peripheries of the top 90 are formed with upper and lower circular rings 94 and 95, the upper ring 94 being

supported on the annular shoulder 96 of the standard 60 while the lower circular ring 95 is carried by the upper surface of the cylindrical member 86.

The cylindrical member 86 has a plurality of illuminating lamps 98 carried thereby with the brackets 100 extending to the interior of the cylindrical member 86. The upper disk 50 is also provided with a plurality of illuminating lamps 98. Electrical conducting wires 102 connect the lamps 98 with the brushes 104 and 106 which are reciprocably carried by the brush holders 108 and 110. The brush holders 108 and 110 are carried by the upper disk 50 so that the brushes 104 and 106 are frictionally engageable with the rings 38 and 36, respectively.

The upper disk 50 has a plurality of radially aligned supporting elements 112, 114 and 116. Each of the groups of aligned elements 112, 114 and 116 is formed with aligned apertures 118, 120 and 122. A crank rod 124 has end and intermediate portions rotatably carried by the elements 112, 114 and 116. The portion of the crank rod 114 disposed between the elements 114 and 116 is provided with a pair of offset portions 126 and 128 providing cranks. A bearing element 130 is secured to the crank rod 124 for maintaining the same in predetermined relation to the supporting elements. The radially inner end of the crank rod 124 is formed with a bevel pinion 132 which is engageable on the bevel gear 34.

Each of the crank portions 126 and 128 has a downwardly extending supporting rod 134 rotatably carried thereby. Each of the supporting rods 134 has a simulated "flying horse" element 136 secured thereto, a portion of the rod 134 extending below the simulated animal element.

The lower disk 56 is formed with a plurality of tubular elements 138 which are adapted to receive the lower end portions of the rods 134.

Looking now at Figure 4, it will be seen that the double switch 42 controls the parallel circuits for the illuminating lamps and the drive motor M. The switch 42 can be closed to supply current to the parallel circuits for the lamps 98 and the motor M. Operation of the motor M will effect rotation of the standard 60. It will be seen that as the standard 60 rotates, the upper disk 50 will rotate therewith carrying the crank rods 124 therewith. Movement of the crank rods 124 with the bevel pinion 132 engaged in the bevel gear 134 will effect rotation of the crank rods 124 whereby reciprocation of the simulated animal elements 136 will be effected.

At the same time the merry-go-round is actuated for rotation, the music box 78 will be actuated by means of the pulley belt 84.

Furthermore, in view of the contact between the brushes 104 and 106 and the annular rings 38 and 36 respectively, electrical power will be supplied to the illuminating lamps 98 whereby the same can be continuously illuminated.

For decorative purposes, the top 90 can be pro-

vided with alternately colored sections 91 and plain sections 93. A plurality of flags 97 can be provided for securing to the top 90 so that the merry-go-round in its entirety will simulate a full-scale merry-go-round.

Having described the invention, what is claimed as new is:

1. A toy merry-go-round comprising a supporting base, a standard rotatably mounted on said supporting base and projecting vertically therefrom, an intermediate portion of said standard being rotatably journaled in a circular bearing plate spaced above said supporting base, said bearing plate being supported by downwardly and outwardly extending supports having lower ends secured to said supporting base, an enlarged disc carried by said standard above said bearing plate for rotation with the standard, motor means carried by said supporting base in driving engagement with said standard, a lower annular plate disposed adjacent said supporting base and suspended from said disc for rotation therewith, said bearing plate being provided with a toothed annular peripheral surface, bevelled gears engaged with said toothed surface, said bevelled gears being mounted on crank arms supported beneath said disc by depending bearing blocks, a plurality of rods extending between said crank arms and said lower plate, simulated animals mounted on said rods adapted to be vertically reciprocated by said crank arms electric lights carried by said disc with portions thereof projecting therethrough, a power source for said electric lights including concentric conductive rings carried by the upper surface of said bearing plate, contact fingers extending downwardly through said disc in engagement with said conductive rings, electrical energy being supplied to said conductive rings by conductors passing through said bearing plate and secured to the undersides of said conductive rings.

2. The toy merry-go-round of claim 1 wherein a music box is carried by said supporting base, said music box being drivingly connected to said standard, said motor means and said music box being disposed within the lower annular plate.

LLOYD L. McDONALD.
